UNITED STATES PATENT OFFICE.

ALWIN H. BECK AND EDWIN S. MIX, OF ROCHESTER, NEW YORK, ASSIGNEES TO HICKOK MANUFACTURING COMPANY, INC., OF ROCHESTER, NEW YORK, A CORPORATION OF NEW YORK.

CLAMPING MEMBER FOR BELT BUCKLES.

Application filed March 19, 1924. Serial No. 700,415.

The present invention relates to a clamping member for belt buckles, an object of this invention being to provide a clamping member made from a single piece of sheet material so that a stronger and less expensive structure is provided.

To these and other ends, the invention consists of certain parts and combinations of parts, all of which will be hereinafter set forth; the novel features being pointed out in the appended claims.

In the drawings:

Fig. 1 is a perspective view of a flat sheet metal blank from which the clamping member is formed;

Figs. 2 to 11 show in perspective successive steps in the operation of forming the clamping member; and

Fig. 12 is a perspective view of the completed clamping member.

Referring more particularly to the drawings and particularly to Fig. 1, 1 and 2 indicate two end portions of a blank, the end portion 2 being slightly larger in width and length than the end portion 1 and the two end portions being connected by a central portion 3, narrower than both of the end portions and having projections or enlargements 4 on opposite sides. This blank is submitted to a number of successive pressing or stamping operations. The result of the first operation on the blank is illustrated in Fig. 2. In this operation, a portion of the central portion 3 of Fig. 1 is pressed to form a bar portion or rib 3^a with closed ends 4^a, the extensions or projections 4 of Fig. 1 being utilized in the production of these closed ends 4^a. The next operation forms serrations or teeth 3^b on the hollow bar portion, as illustrated in Fig. 3. The next operation trims the end portions or leaves in the manner shown in Figs. 1^a and 2^a, Fig. 4, providing, at the same time, notches 2^x between the central portion and the leaf 2^a and trimming the central portion on opposite sides of the bar portion 3^b, so that lips 3^x remain on the opposite ends of the bar portion 3^b. The next operation turns a flange 2^y laterally from the portion 2^b and projects the portion 3^x of Fig. 4 into the plane of the end portions of the hollow bar 3^b as indicated at 3^y. The next operation as illustrated in Fig. 6 merely removes the end portions of 3^y as shown in

Fig. 5 so that the lower edges of the ends 55 of the bar 3^b coincide with the under side of the end portions 1^a and 1^b. The next operation illustrated in Fig. 7 bends the portion 2^b of Fig. 6 so that it lies in a plane with the adjacent side wall of the bar. The 60 operation illustrated in Fig. 8 occurs next and in this the portion 2^b of Fig. 7 is bent at an angle to the adjacent side face of the bar 3^b. By the operation illustrated in Fig. 9, the two end portions are brought into 65 overlapping relation, the end portion 1^a being received within the marginal flange 2^y. The operation effecting the result illustrated in Fig. 10 consists in bending the 70 marginal flange 2^y inwardly to provide a rib or seam 2^z, overhanging the portion 1^a and holding such portion to the portion 2^b.

The operation effecting the result shown in Fig. 11 consists in cutting the two end portions 1^a and 2^b to provide coincident 75 openings 5, whereas the operation which produces the final article illustrated in Fig. 12 consists in perforating the opposite end walls of the bar 3 as at 6.

It will thus be apparent that this method 80 gives a clamping member for a belt buckle in which the bar portion is formed from sheet metal and is of hollow form. From opposite edges of this bar portion 2, leaves 85 formed by the end portions 1 and 2 of the blank of Fig. 1 extend, one outwardly from the bar and the other inwardly to close the inner face of the bar and to overlap the leaf proceeding from the other edge of the bar. One of these leaves has a flange at its edge 90 bent to overhang the other leaf and both leaves are provided with coincident openings forming from themselves a loop with which one end of a belt may engage.

What we claim as our invention and desire to secure by Letters Patent is:

1. A clamping member for belt buckles comprising a bar portion, and two leaves extending from opposite sides of said bar portion, one of said leaves overlapping the other.

2. A clamping member for belt buckles comprising a bar portion, and two leaves extending from opposite sides of said bar portion, one of said leaves overlapping the other and one of said leaves thereof having an edge bent over an edge of the other leaf.

3. A clamping member for belt buckles

comprising a belt portion, and two leaves extending from opposite sides of the belt portion, one of said leaves overlapping the other leaf and both leaves having coincident openings.

4. A belt buckle clamping member comprising a hollow bar portion, two leaves ex-

tending from opposite sides of the bar portion, one being bent to overlap the other, one of said leaves having its edges bent to ¹⁰ overhang the edges of the other and both leaves having coincident openings.
